UNITED STATES PATENT OFFICE.

ETIENNE SALOMON, OF MONTREAL, QUEBEC, CANADA, ASSIGNOR OF ONE-HALF TO JOSEPH REBER, OF SAME PLACE.

PRESSURE REGULATOR AND DISTRIBUTER.

SPECIFICATION forming part of Letters Patent No. 240,549, dated April 26, 1881.

Application filed October 11, 1880. (Model.)

To all whom it may concern:

Be it known that I, ETIENNE SALOMON, of the city and district of Montreal, in the Province of Quebec and Dominion of Canada, machinist, have invented certain new and useful Improvements in Pressure Regulators and Distributers, of which the following is a specification.

These improvements are fully set forth in the following specification and accompanying drawing.

My invention relates to a novel and automatic apparatus for regulating, distributing, and shutting off compressed air or other gases or fluids at any desired pressure. It is intended for the use of chemists, druggists, grocers, dealers in liquors, (being adapted for use as a beer-pump,) and for many other purposes. Its superiority over all other apparatus hitherto in use for the same purpose consists in its greater compactness, simplicity, efficiency, and economy.

My improved apparatus consists, essentially, of a reservoir of sufficient capacity and capable of sustaining the greatest pressure of air or other fluid which may at any time be applied by means of an air-pump or otherwise. This is connected, by a pipe furnished with a regulating stop-cock or valve, to a vessel preferably of a cylindrical form, divided into two compartments by a diaphragm, on one side of which the cylinder communicates with the reservoir, as before mentioned, and on the other, by means of the distributing pipe or pipes, with the surface of the liquids, &c., contained in the casks, vats, or other vessels to be operated upon.

The subordinate parts of the mechanism, hereinafter to be described, connected with both compartments, respectively, are so arranged that by their mutual action the varying pressure of the reservoir may be modified at pleasure with the utmost delicacy and precision, so as to pass into the distributing-pipes at any required degree.

The accompanying drawing represents a vertical section of my complete apparatus, which will suffice to explain all its features.

Letter A represents the reservoir, which is to be supplied, by means of an air-pump or oth-

erwise through the inlet-pipe a, with air, gas, or other fluid at a pressure sufficiently high for all purposes required; B, the regulating-chamber, preferably of a cylindrical form, divided into two compartments, B and B', by the diaphragm C, one one side of which the pipe D, furnished with a stop-cock or valve, E, connects the chamber B with the reservoir A.

The cylinder B is bored out and fitted with an air-tight piston, F, whose rod b communicates motion to a lever, G, having its fulcrum or center of motion at c, and provided with an adjustable weight or counter-balance, H, which may be regulated by hand to any required degree. The lever G is connected, by means of a rod, d, to the stop-cock E, and this mechanism is so arranged that the motion of the piston F will tend to open or close the stop-cock or valve E at the same time that the motion of the piston F is controlled and regulated by the position of the adjustable weight H.

It will thus be seen that when the pressure in the cylinder B is such as to counterbalance the regulated pressure transmitted through the lever G to the piston F, the latter will remain in equilibrium and no motion of the parts will ensue. On the other hand, as soon as this equilibrium is disturbed by the reduction of pressure in the reservoir or by increased or diminished flow from the distributing-pipes the piston will rise or fall, and thereby open or close (more or less) the regulating stop-cock or valve E.

A hole, e, in the cover of the cylinder B is provided for the purpose of admitting the external air to the outer side of the piston F, for the purpose of relieving it from any pressure tending to interfere with its free action on the inner side.

The second division of the apparatus on the other side of the diaphragm C consists of the following or equivalent mechanism: A conical valve, f, is fitted air-tight to the outer surface of the diaphragm C concentric with the cylinder and having its stem projecting outwardly and adapted to pass through and to slide up and down in the diaphragm freely, but without lateral motion. A passage, g, is, however, provided in the stem immediately above the valve, to admit of the air passing

freely between both sides of the diaphragm when the valve *f* is opened.

To the opposite end of the stem, which is sufficiently long to admit of the requisite space 5 in the cylinder *B'* for the distributing pipe or pipes *J* provided with suitable stop-cock *h*, is attached a rubber disk or washer, *j*, suitably protected by metallic plates, and forming an air-tight cover for the cylinder *B'*, but capable of moving up and down with the valve *f*. It is pressed upward by a slight spiral spring, *K*, and downward by a similar though stronger spring, *L*, which may be regulated to any required degree of tension by a fine-threaded 15 screwed plug, *M*, worked by a hand-wheel or key, *N*. In connection with the plug *M* is an index or pointer, *k*, which is carried up and down with the plug, and serves to regulate and indicate, by a graduated scale, *l*, upon the 20 outer casing of the spring *L*, the degree of tension on the spring, and consequently the degree of pressure at which the air or other fluid is allowed to pass through the distributing pipe or pipes *J*.

25 The action of the entire apparatus is as follows: When the pressure in the cylinder *B* from the reservoir *A* is such as to counterbalance the adjustable weight *H*, the spring *L* being also set to the required pressure, the air or 30 other gas from the cylinder *B* passes freely through the valve *f* and passage *g* into the regulating-chamber *B'*, thereby raising the rubber washer *j* and closing the valve *f* when the pressure in both compartments *B* and *B'* are 35 equal. The efflux of the air or other fluid through the distributing-pipe *J* will reduce the pressure in the cylinders *B* and *B'*, which, through the action of the piston *F*, will cause the counter-balance *H* to descend, thereby 40 opening the stop-cock or valve *E* to admit a further supply of air at an increased pressure from the reservoir *A*. At the same time the spring *L*, pressing upon the movable rubber washer or elastic diaphragm *j*, opens the valve 45 *f*, thus equalizing the pressure on both sides of the diaphragm *C*, the small spring *K* tending to counteract any undue pressure from the spring *L*. Thus, when the index *k* points to zero there will be no pressure on the spring 50 *L*. Consequently the small spring *K* will close the valve *f*, there being then no pressure either in the chamber *B* or *B'*. On the other hand,

when the index is set at 10, as in the drawing, the counter-balance *H* being also adjusted to the same figure, a pressure of ten pounds on 55 the square inch will be constantly and regularly maintained in the distributing-pipe *J*, notwithstanding any variation within reasonable limits of the pressure in the reservoir *A*.

By applying another distributing-pipe, *J'*, to 60 the first compartment, *B*, and adjusting the weight *H* accordingly, two different degrees of pressure may be obtained at one and the same time.

Having thus fully described the nature and 65 operation of my invention, what I claim as new, and desire to secure by Letters Patent is as follows, viz :

1. In combination with a reservoir containing air or other gas or fluid under pressure, a 70 regulating-chamber divided into two compartments by an air-tight diaphragm or partition having an intermediate regulating-valve, one being connected with the supply and the other with the distribution, each compartment being 75 provided with a movable air-tight piston or elastic disk or washer, both of which are capable of being regulated by adjustable weights or springs to any required degree, one actuating the supply and the other the distribution 80 valve or stop-cock, by the mutual action of which the pressure may be regulated, distributed, or shut off at pleasure.

2. The combination of the chamber *B*, divided into two compartments, *B* and *B'*, by an 85 air-tight partition, *C*, as specified, with the piston *F* or movable air-tight disk or washer, adjustably-weighted lever *G* or spring pressing the piston inwardly with any required degree of pressure, the connecting-rod *d*, actuating the stop-cock or valve *E*, the valve *f*, passage *g*, springs *K* and *L*, or their equivalent, 90 capable of exerting a regulated pressure upon the valve *f*, elastic air-tight washer or piston *j*, screwed plug *M*, index *k*, and graduated 95 scale *l*, all relatively arranged and operating with the reservoir *A* and distributing pipe or pipes *J* *J'*, substantially as and for the purposes specified.

ETIENNE SALOMON.
